UNITED STATES PATENT OFFICE.

ALONZO E. RHOADES, OF HOPEDALE, MASSACHUSETTS, ASSIGNOR TO DRAPER CORPORATION, OF HOPEDALE, MASSACHUSETTS, A CORPORATION OF MAINE.

FILLING-REPLENISHING FEELER-LOOM AND FILLING-CARRIER THEREFOR.

1,243,342.

Specification of Letters Patent.

Patented Oct. 16, 1917.

Application filed January 16, 1917. Serial No. 142,736.

To all whom it may concern:

Be it known that I, ALONZO E. RHOADES, a citizen of the United States, residing at Hopedale, county of Worcester, State of Massachusetts, have invented an Improvement in Filling-Replenishing Feeler-Looms and Filling-Carriers Therefor, of which the following description, in connection with the accompanying drawing, is a specification, like characters on the drawing representing like parts.

This invention relates to looms provided with mechanism for automatically replenishing the filling when the supply in the running shuttle has become exhausted to a predetermined extent. In this type of loom it is necessary to leave upon the filling carrier in the running shuttle a definite amount of filling, usually such an amount as will enable one or two picks to be made after detection has taken place. It is desirable further that there shall be left upon the filling carrier no more than the required amount because not only is any surplus wastage, but time and labor are involved in removing the surplus from the filling carrier prior to spinning thereon a fresh supply. It is the object of the present invention to provide a feeler mechanism and a filling carrier co-operating therewith which shall insure detection of substantial exhaustion of filling regardless of the position of the filling carrier in the shuttle and within a considerable range of position of the shuttle longitudinally with respect to the feeler as for example when the shuttle is not accurately boxed.

This object of the invention is secured primarily by a filling carrier of novel construction in that it has a zone of its barrel provided with an endless circumferential series of equally spaced helical grooves and co-operating therewith a plurality of separated feelers independently and intermittently engaging the filling on the filling carrier in a line parallel with the axis thereof and so arranged that one or more of the helical grooves whatever may be the rotary position of the filling carrier in the shuttle, and within reasonable limits whatever may be the longitudinal position of the filling carrier or shuttle with respect to the feelers on absence of filling will be opposite the said feeler or feelers which will cause the initiation and operation of the filling replenishing mechanism and leave a substantially prede-

termined quantity of filling on the filling carrier after detection takes place.

The invention therefore involves a novel form of feeler motion and novel mechanism for transmitting indication of filling exhaustion to the filling replenishing mechanism.

These and other objects of the invention will appear more fully from the accompanying description and drawings and will be particularly pointed out in the claims.

The drawings show so much of an ordinary automatic filling replenishing loom, such, for example, as the well known "Northrop" type as is necessary to a disclosure of the present invention.

In the drawings,

Figure 1 is a top plan view of the left hand or detecting end of an automatic filling replenishing loom with a preferred form of the present invention embodied therein;

Fig. 2 is a left hand end elevation of the parts shown in Fig. 1, partially in cross section and partially broken away;

Fig. 3 is a view in vertical cross section showing the ends of the latch and weft hammer;

Fig. 4 is a top plan view of the feelers, feeler support and stand with the cover of the latter removed.

Fig. 5 is a central vertical cross section of the feeler stand and connected parts;

Fig. 6 is a side elevation of the butt end of a filling carrier embodying the invention;

Fig. 7 is a transverse sectional view of the filling carrier shown in Fig. 6 taken through the helical grooved zone;

Fig. 8 is a rear end elevation of the feelers, feeler support and stand.

The present invention being concerned in its novel features only with the mechanism for securing detection of filling exhaustion and thereupon initiating the operation of the filling replenishing mechanism it is unnecessary to illustrate or describe the remaining mechanism of an automatic filling replenishing loom all of which is well known and familiar to those skilled in the art.

It will be sufficient therefore to note that the breast beam 1 supports at the front a controller rock shaft 2 which extends to, and in the usual and well known manner when rocked, initiates the operation of a suitable filling replenishing mechanism to cause a fresh filling carrier to be transferred therefrom into the shuttle boxed therebeneath and

at the same time eject from the shuttle the second filling carrier.

The controller rock shaft 2 is usually provided with an upstanding rocker arm 3 to the upper end of which is pivoted a latch 4 which extends rearwardly over the breast beam and at its rear end co-operates with the ordinary weft hammer 5. The weft hammer is provided with a depending shoulder 6 and the latch is provided with a rearwardly extending finger 7. When the loom is in operation and sufficient filling is upon the filling carrier the mechanism operates to keep the finger 7 of the latch beneath the path of the shoulder 6 of the weft hammer when the upper end of the weft hammer swings rearwardly but when the filling on the filling carrier in the running shuttle is substantially exhausted and detection takes place the mechanism operates to raise the latch 4 to bring the finger 7 into the path of the shoulder 6 so that when the weft hammer swings forwardly it carries with it the latch, rocks the controller shaft 2, and thus initiates the operation of the filling replenishing mechanism.

As has already been pointed out the invention involves a novel form of filling carrier which is herein shown in the form of a bobbin 8 provided with a butt 9 having the usual retaining rings 10. This bobbin is carried by a shuttle 11 shown in Fig. 1 boxed at the detecting end of the lay 12. This filling carrier or bobbin has a zone 13 of its barrel adjacent the butt 9 provided with an endless circumferential series of equally spaced helical grooves 14. The depth of these grooves is sufficient to enable a feeler to enter therein and have sufficient movement to secure the operation of the transmitting mechanism. The length of these helical grooves and consequently the length of the zone 13 is sufficient to enable a plurality of separated independently movable feelers 16 to be arranged opposite even when the longitudinal position of the filling carrier with respect to the feelers is varied as by a slightly improper boxing of the shuttle. The pitch of the helices upon which the grooves are formed should be comparatively slight and a preferred pitch is illustrated. The helical ribs 15 which separate the grooves 14 are preferably of less width than the grooves.

It will thus be seen that there is presented a novel construction of filling carrier which may be placed in the shuttle without regard to the particular angular position or positioned rotarily of its axis which it occupies in the shuttle. This is because the circumferential series of equally spaced helical grooves present a substantially similar face to the row of feelers regardless of the angular position of the shuttle. This renders it unnecessary to provide any mechanism in

connection with the filling replenishing mechanism to guide the filling carrier or control its delivery to the shuttle so as to cause it to present any definite angular position with respect to the shuttle. This helical series of grooves when co-operating with a row of independently acting feelers insures that one or more of the feelers will be opposite a groove no matter what may be the rotary position of the filling carrier and thus upon the beat up insures that a detecting action of one or more feelers shall take place when filling is absent opposite the feelers.

The feeler motion herein illustrated as a preferred form of the invention for co-operating with the helically grooved filling carrier comprises a plurality of feelers 16 preferably arranged in a row side by side with their ends on a line opposite the axis of the filling carrier when the shuttle is at the detecting side of the loom. These feelers have their ends or points inclined to correspond in general with the pitch of the helical grooves 14 so as more readily to enter therein. The feelers 16 are separated preferably equi-distantly and preferably by distances greater than the distance between the center lines of the helical grooves where the grooves cross a line on the barrel periphery parallel with the barrel axis. This space relation of the feelers to the helical grooves aids in insuring that, when the filling is absent from the grooved zone of the barrel when the beat up takes place, one or more of the feelers may enter one or more of the helical grooves whatever may be the rotary position of the filling carrier.

The feelers 16 are each provided with an upstanding lug 17 and are independently longitudinally and slidably mounted in a feeler support 18 shown as a flat box-like structure recessed to receive the feelers and slotted at 19 to allow the projection of the lugs 17 and closed at the bottom by a plate 20. Each feeler is normally held rearwardly projected by a helical spring 21 seated in the bore in the feeler support 18 and abutting the head of a plunger 22 which in turn abuts the forward end of the feeler.

The feeler support 18 itself is slidably mounted in a feeler stand 23 shown as a box-like casing provided with a cover 24. The cover and bottom portion of the stand are laterally flanged at 25 and 26 respectively and secured together by set screws 27. The flanges 25 and 26 are longitudinally slotted at 28 and set screws 29 passing through the said slot 28 serve longitudinally and adjustably to secure the feeler stand to a bracket 30 in turn secured by a bolt 31 to a depending flange 32 of the breast beam. Set screws 33 provided with lock nuts 34 are threaded through an upwardly projecting flange 35 of the bracket 30 and abut the edge of the flanges 25 and 26 and secure a

lateral adjustment of the feeler stand, the slot 28 being of greater width than the diameter of the set screws 29.

The feeler support 18 is longitudinally 5 slidably mounted in the feeler stand 23 and is provided with a forwardly projecting cylindrical shank 36 guided in the forward end of the stand. This shank is surrounded by a helical spring 37 abutting at one end 10 against the interior of the forward end of the stand and at the other end against the feeler support 18 so that the feeler support as a whole is yieldingly held normally projected rearwardly, a depending lug 38 therefrom contacting with the rearward end of the stand to limit the rearward projection. The tension of the spring 37 is considerably greater than that of the combined springs 21 so that the feelers may all yield forwardly without moving the feeler support but if considerable pressure comes upon the feelers as by the feelers contacting with the shuttle wall when the shuttle is improperly boxed then the entire feeler support will 20 move forwardly thus obviating any danger of a smash or breakage of the parts.

A controller member 39 shown as a flat plate of sufficient width to cover the entire series of feelers and provided with a rearward depending projection 40 forming a hook is secured by set screws 41 to a shaft 42 pivoted in upstanding lugs 43 formed on or connected with the cover 24 of the feeler stand 23 and is so proportioned that 30 when the feeler support and feelers are in their normal position rearwardly projecting the projection 40 will rest upon the top of lugs 17 and be maintained thereby in elevated position.

40 The shaft 42 forms a portion of a transmitter for transmitting the detecting action to the filling replenishing mechanism. In order to allow of adjustment of the feeler stand and provide facility in assembling the 45 parts this transmitting mechanism is jointed as by pivotally connecting the shaft 42 at 44 to a socketed head 45 in turn longitudinally and rotarily adjustably connected by set screws 46 to a shaft 47. This shaft at 50 the right hand end is journaled in a bearing 48 formed on a bracket 49 secured by a set screw 50 to the breast beam.

At its right hand end the shaft 47 is formed into a crank 51 and enters a longitudinal slot 52 in the latch 4. A helical spring 53 surrounds the shaft 47 and is secured at one end to the bearing 48 and at the other end to a collar 54 rotarily adjustable on the shaft 47 by means of a set screw 55 and normally acts to depress the rearward end of the controller 39, and consequently through the crank 51 the rear end of the latch 4 to cause the finger 7 of the latch to pass beneath the path of the shoulder 6 of 60 the weft hammer.

When the helical grooves of the filling carrier are covered with filling and the lay beats up the feelers 16 enter the opening 56 in the shuttle binder 57 and the opening 58 in the wall of the shuttle 11 and contact with 70 the filling on the filling carrier. The filling carrier therefore forces the feelers forwardly against the helical springs 21 and the lugs 17 pass forward of the projection 40. The controller 39 is thereupon depressed by the 75 action of the spring 53 and the rear end of the latch 4 is simultaneously depressed through the action of the crank 51 so that as the weft hammer swings forwardly it clears the finger 7 of the latch. Consequently there is no operation of the controller rock shaft 2 and no initiation of 80 filling replenishing action.

Upon the return of the lay the feelers have now been locked in forward position by 85 the controller 39 and mechanism is therefore provided to restore the controller to raised position to allow the feelers to move rearwardly. In the construction illustrated for this purpose this action is secured through 90 the movement of the weft hammer. The shaft 47 is provided with a depending crank arm 59 formed on a bracket 60 surrounding and secured to the shaft by set screws 61. A rearwardly projecting link 62 is pivoted 95 to the lower end of the crank arm 59 and is provided at its rear end with a longitudinal slot 63 resting over a pin 64 projecting laterally from the upper end of the weft hammer 5. A cotter pin 65 holds the link in 100 place on the pin 64. The slot 63 is so positioned with respect to the pin 65 that as the weft hammer swings rearwardly it pulls the link 62 thus rocking the shaft 47 and raising the controller 39 against the action 105 of the spring 53 until the projection 40 of the controller clears the lugs 17 and allows the feelers 16 to swing rearwardly to carry the lugs 17 beneath the projection 40.

The operation of the mechanism will be 110 apparent from the foregoing description. Filling carriers are wound so that when the zone 13 covered by the helical grooves is uncovered by the drawing off of the filling in the weaving operation there will remain 115 upon the filling carrier a predetermined amount of filling required to continue the weaving operation until replenishment takes place through the action of the filling replenishing mechanism. Upon the next detecting beat of the lay the feelers 16 will contact with the uncovered zone 13 of the filling carrier and by reason of the relation of the feelers to the helical grooves already explained one or more of the feelers will 120 enter the grooves so that as the beat up is finished the one or more feelers which are in the grooves will not be carried forwardly sufficiently to clear the projection 40 of the controller 39 and the controller will remain 125 130

elevated thus holding the latch 4 elevated and the finger 7 in the path of the shoulder 6 of the weft hammer so that as the weft hammer moves forwardly the latch will be 5 rocked forwardly and the operation of the filling replenishing mechanism will be initiated in the usual manner. Upon the rearward movement of the lay the controller 39 being held elevated by the feelers not carried forward, those feelers which have been 10 carried forward will spring back to normal position with their lugs 17 beneath the controller. During the normal operation of the loom and before the filling has been exhausted to an extent sufficient to uncover 15 the zone 13 upon each beat up the filling carrier contacting with the feelers 16 will move all of the feelers forwardly against their springs allowing the controller 39 to drop 20 behind the lugs 17. Upon the rearward beat of the lay and the rearward movement of the weft hammer the link 62 will rock the shaft 47 to restore or elevate the controller 39 and allow the feelers to spring forwardly 25 bringing their lugs 17 beneath the controller. If the shuttle be improperly boxed to such an extent that any of the feelers come in contact with the shuttle wall then upon the 30 beat up of the lay the feeler support will slide forward rearwardly against the tension of its spring 37 preventing any breakage of the parts.

Having fully described my invention what I claim as new and desire to secure by Letters Patent is:

- 35 1. In an automatic filling replenishing loom comprising filling carriers, each having a zone of its barrel provided with an endless circumferential series of equally spaced helical grooves; filling replenishing mechanism; feeler mechanism including a plurality of separated feelers independently and intermittently engaging the filling on the filling carrier in the shuttle, whereby upon the detecting beat up, when the grooved zone of the running filling carrier is uncovered of filling, one or more grooves will be entered by one or more feelers, regardless of the rotary, or exact longitudinal, position of the filling carrier; and connections between said filling replenishing mechanism and feeler mechanism acting to initiate the operation of the filling replenishing mechanism upon the entrance of a feeler into a groove.
- 40 2. In an automatic filling replenishing loom comprising filling carriers, each having a zone of its barrel provided with an endless circumferential series of equally spaced helical grooves; filling replenishing mechanism; feeler mechanism including a plurality of feelers separately and independently mounted in said feeler support and independently and yieldingly projected rearwardly with 45
- 45
- 50
- 55
- 60
- 65

shuttle, whereby upon the detecting beat up, when the grooved zone of the running filling carrier is uncovered of filling, one or more grooves will be entered by one or more feelers, regardless of the rotary, or exact longitudinal, position of the filling carrier; and connections between said filling replenishing mechanism and feeler mechanism acting to initiate the operation of the filling replenishing mechanism upon the entrance of a feeler into a groove.

3. In an automatic filling replenishing loom comprising filling carriers, each having a zone of its barrel provided with an endless circumferential series of equally spaced helical grooves; filling replenishing mechanism; feeler mechanism including a plurality of feelers separated by spaces greater than the spaces which separate the helical grooves and independently and intermittently engaging the filling on the filling carrier in the shuttle, whereby upon the detecting beat up, when the grooved zone of the running filling carrier is uncovered of filling, one or more grooves will be entered by one or more feelers, regardless of the rotary, or exact longitudinal, position of the filling carrier; and connections between said filling replenishing mechanism and feeler mechanism acting to initiate the operation of the filling replenishing mechanism upon the entrance of a feeler into a groove.

4. An automatic filling replenishing loom comprising means for initiating filling replenishment; feeler mechanism including a plurality of separated independently and yieldingly projected feelers; a controller held in elevated position by or through the feelers when rearwardly projected and depressed when the feelers are moved forwardly by contact with the filling on the filling carrier; and means for restoring the controller to elevated position after each beat up of the lay.

5. An automatic filling replenishing loom comprising means for initiating filling replenishment; feeler mechanism including a plurality of separated independently and yieldingly projected feelers; a controller held in elevated position by or through the feelers when rearwardly projected and depressed when the feelers are moved forwardly by contact with the filling on the filling carrier; and means operated by the weft hammer for restoring the controller to elevated position after each beat up of the lay.

6. An automatic filling replenishing loom comprising means for initiating filling replenishment; feeler mechanism including a movable feeler support, a spring for projecting said feeler support rearwardly and permitting it to yield forwardly, a plurality of feelers separately and independently mounted in said feeler support and independently and yieldingly projected rearwardly with

- respect to said support; and connections between said means for initiating filling replenishment and said feeler mechanism acting to operate the former upon the failure of any one or more of said feelers to move forwardly a predetermined extent with respect to the feeler support upon the detecting beat up.
7. An automatic filling replenishing loom comprising means for initiating filling replenishment; feeler mechanism including a movable feeler support, a spring for projecting said feeler support rearwardly and permitting it to yield forwardly, a plurality of feelers separately and independently mounted in said feeler support and independently and yieldingly projected rearwardly with respect to said support; a controller pivotally mounted on the feeler support and held in elevated position by or through the feelers when one or more are rearwardly projected and depressed when all of the feelers are moved forwardly by contact with the filling on the filling carrier; and connections between the said controller and the means for initiating filling replenishment whereby when the controller remains elevated on the beat up the said means will be operated.
8. An automatic filling replenishing loom comprising feeler mechanism, including a plurality of separated independently and yieldingly rearwardly projected feelers; a controller held in elevated position by or through the feelers when one or more are rearwardly projected and depressed when all of the feelers are moved forwardly by contact with the filling on the filling carrier; a shaft connected and movable with the controller; a constantly vibrating weft hammer; means for initiating filling replenishment including a latch; and a connection between said shaft and said latch whereby when the controller is elevated the latch will be positioned in the path of the weft hammer thereby to initiate filling replenishment.
9. An automatic filling replenishing loom comprising feeler mechanism including a plurality of separated independently and yieldingly rearwardly projected feelers; a controller held in elevated position by or through the feelers when one or more are rearwardly projected and depressed when all of the feelers are moved forwardly by contact with the filling on the filling carrier; a shaft connected and movable with the controller; a constantly vibrating weft hammer; means for initiating filling replenishing including a latch; a connection between said shaft and said latch whereby when the controller is elevated the latch will be positioned in the path of the weft hammer thereby to initiate filling replenishment; and means connected to the said shaft and oper-

ated by the weft hammer to restore the said controller to elevated position at each rearward movement of the bay.

10. An automatic filling replenishing loom comprising means for initiating filling replenishment; a yieldingly rearwardly projecting feeler support; a plurality of separated feelers independently mounted in the feeler support and yieldingly rearwardly projected with respect thereto; each of said feelers provided with a projecting lug; a controller pivotally mounted on the feeler support and presenting a downward projection forming a hook and normally resting on the said lugs when the feelers are rearwardly projected; a transmitting shaft connected to said controller; a pivoted latch connected to and acting when forwardly projected to operate said means for initiating filling replenishment; a connection between said transmitting shaft and said latch and a connection between said transmitting shaft and said weft hammer whereby when the controller is in depressed position the latch will be held out of the path of the weft hammer and when the controller is in elevated position the latch will be struck and operated by the weft hammer upon its forward movement, and whereby the weft hammer on its rearward movement will give a reverse rotation to the shaft and restore the controller to elevated position.

11. In an automatic filling replenishing loom, feeler mechanism including a plurality of separated independently and yieldingly projected feelers having their ends or points similarly inclined whereby any one or more of the said points may enter one or more equally spaced helical grooves in the barrel of an opposed filling carrier.

12. An automatic filling replenishing loom comprising means for initiating filling replenishment; a yieldingly rearwardly projected feeler support, a plurality of separated feelers independently mounted in said feeler support and yieldingly rearwardly projected with respect thereto; a controller mounted on the feeler support and held in elevated position by or through the feelers when rearwardly projected and depressed when the feelers are moved forwardly by contact with the filling on a filling carrier; a two-part jointed transmitter shaft connected to the controller and acting when operated thereby to operate the means for initiating filling replenishment, the said joint in the transmitter shaft permitting forward and rearward movement of the feeler support to take place without interfering with the operation of the means for initiating filling replenishment from the controller.

13. As a new article of manufacture, a filling carrier for looms having a zone of its

barrel provided with an endless circumferential series of equally spaced helical grooves.

14. As a new article of manufacture, a filling carrier for looms having a zone of its

barrel provided with an endless circumferential series of equally spaced helical grooves laterally separated at the surface of the barrel by ribs narrower than the width of the grooves.

In testimony whereof, I have signed my 10 name to this specification.

ALONZO E. RHOADES.
